ATTORNEY

UNITED STATES PATENT OFFICE.

ELMER A. PETERSON, OF ALVIN, ILLINOIS.

STOVEPIPE.

1,288,163.

Specification of Letters Patent. Patented Dec. 17, 1918.

Application filed June 8, 1918. Serial No. 238,956.

To all whom it may concern:

Be it known that I, ELMER A. PETERSON, a citizen of the United States, residing at Alvin, in the county of Vermilion and State 5 of Illinois, have invented certain new and useful Improvements in Stovepipes, of which the following is a specification.

This invention relates to a stove pipe and has for its principal object the production 10 of an efficient means for holding the stove pipe against disassembly when in use.

One object of this invention is the production of a stove pipe connection which consists of a clamping band which is bound 15 in engagement with a plurality of pipes at the joint thereof, thus holding the two sections of the pipe in positive engagement with each other and forming a smoke tight joint.

20 Another object of this invention is the production of a stove pipe connection for connecting the pipes in engagement with the chimney to which the same is attached.

Another object of this invention is the 25 production of a stove pipe connection which consists of a thimble to engage a section of a stove pipe, together with an expanding means for binding the thimble in engagement with the chimney.

30 Broadly stated, the invention consists of a plurality of interengaging stove pipes, clamping bands positioned upon the junctions of the pipe, means for drawing the ends of the bands together for holding the 35 pipe sections in engagement with each other, a thimble engaging one of the sections, a turnbuckle having threaded stems engaged therewith, heads carried upon the ends of said stems and binding within the thimble 40 for binding the thimble in engagement with the chimney, thus holding the sections of the pipe against displacement.

One practical form of construction and assembly of the present invention will be 45 hereinafter described and is illustrated in the accompanying drawing, in which—

Figure 1 is a sectional view through a pair of stove pipe sections, showing the clamping band in place.

50 Fig. 2 is a longitudinal section through the connecting thimble and the stove pipe section, also showing the turnbuckle and the heads thereof in section and illustrating the manner in which the same are used.

55 Fig. 3 is a transverse section through a pair of stove pipe sections, illustrating the

clamping band in side elevation and the manner in which the same is used.

Fig. 4 is a detail perspective view of the sleeve used in connection with the device. 60

Fig. 5 is a detail perspective view of the thimble used in connection with the chimney connecting means.

Fig. 6 is a detail perspective view of a 65 complete clamping band, and

Fig. 7 is a detail perspective view of the turnbuckle and the heads connected thereto by the stems.

In the preferred embodiment of the present invention, about to be described, it will 70 be seen that the device is used in connection with a plurality of stove pipe sections 10 which have unobstructed end portions 11, while the opposite ends thereof are corrugated as indicated at 12 and extend diagonally to the side surfaces of the sections, as 75 indicated at 13. It will also be noted that an annular bead 14 is formed on the section adjacent the corrugated portion 12 thereof, as will be seen by referring to Figs. 1 and 2. 80 It is obvious that by having the end portions cut off diagonally to the sides of the section, as indicated at 13, the corrugated portion 12 may be easily slipped into the unobstructed end portion 11 of the next adjacent section. 85

In order to bind the two sections in engagement with each other there is provided a clamping band, the construction of which is clearly set forth in Figs. 3 and 6. The 90 clamping band 15 is provided with an annular beading 16 while the ends 17 are spaced apart, thus permitting the clamping band 15 to be placed over the end portions of two sections of the stove pipe, while the 95 annular beading 14 of one section fits within the annular beading of the clamping band. This clamping band is provided with plates 18 fixed thereon as indicated at 19 upon each side of the annular beading and 100 also adjacent the ends 17 of the band 15. The plates 18 have sleeves 20 formed thereon which carry the pins 21 having central loops 22. A bolt 23 has an eye 24 carried upon one of the loops 22 while the opposite end 105 of the bolt is removably extended through the remaining loop and carries a winged nut 25. Therefore, it is obvious that as the nut 25 is screwed onto the bolt 23, the bolt will draw upon the loops 22, thus urging the 110 ends 17 of the band 15 toward each other, whereby the band will be clamped upon the

stove pipe section for efficiently holding the same together and also forming a substantially smoke-tight joint.

In order to allow the device to be used in connection with a chimney and prevent its displacement, the sleeve 26 is provided and for this reason is substantially cylindrical and has spurs 27 extending therefrom. In the building of the chimney indicated at 28, 10 having the usual opening therein 29, the sleeve 26 is also built into the chimney to have the spurs 27 extending into the body of the chimney, thus holding the sleeve against displacement and allowing the same 15 to present an even surface in engagement with which the retaining device may be secured.

The thimble comprises a neck 30 having an outstanding annular flange 31 thereon, 20 while the inner end of the thimble is corrugated as indicated at 32. The corrugated portions 32 of the thimble are to be inserted into the sleeve 26 and thus it will be noted that the inward movement of the thimble is 25 limited by the flange 31 engaging the surface of the chimney 28. At this time the neck 30 may be placed in engagement with a section of stove pipe and a clamping band, as hereinbefore described, placed in engagement therewith, as illustrated in Fig. 2.

However, before the connection of a section of stove pipe therewith, the thimble is connected to the sleeve by the device shown in Figs. 2 and 7. This device consists of a 35 turn buckle 33 carrying threaded stems 34. The semi-circular heads 35 are fixed upon the outer ends of the stems 34. These heads are placed in engagement with the corrugated portion 32 of the thimble and then 40 the turn buckle 33 is rotated to cause the semi-circular heads 35 to further bear with greater force upon the corrugated portions 32 of the thimble, which action will tend to slightly expand the corrugated portion to 45 bring about a greater binding action in the sleeve and for this reason it is obvious the thimble will be positively held against any tendency of accidental displacement.

In explaining the operation of the invention, it will be seen that the sleeve is placed 50 in engagement with the chimney when the chimney is being built. It may be stated however, that if so desired, the present invention can be used in an ordinary flue or 55 chimney opening without actually needing the sleeve. The thimble may then be placed in engagement with the sleeve and the turn buckle adjusted to cause the heads 35 to bear more firmly upon the corrugated portion of 60 the thimble to move this corrugated portion into a firmer engagement with the sleeve. A section of stove pipe may then be placed in engagement with the thimble and in engagement with each other and the clamping bands hereinbefore described may then be 65

arranged over the joints of the sections for holding the same in firm engagement and also forming smoke tight joints.

From the foregoing description it will be seen that a very simple and efficient stove pipe section connection has been produced whereby the sections of the stove pipe will be firmly held upon each other in an assembled condition, while the connection of the turn buckle arrangement will positively hold the thimble in engagement with the chimney, thus holding the device in condition for use at all times.

The foregoing description and the drawings have reference to what may be considered the preferred, or approved, form of my invention. It is to be understood that I may make such changes in construction and arrangement and combination of parts, materials, dimensions, et cetera, as may 85 prove expedient and fall within the scope of the appended claims.

Having thus fully described my invention, what I claim as new and desire to secure by Letters Patent, is:

1. In a device of the class described, the combination of a plurality of stove pipe sections, each section having an annular beading thereon, a clamping band having a beading, said clamping band being positioned upon the ends of said sections, while the beading of the sections will fit within the beading of the band, plates fixed upon said band adjacent its ends, said plates having sleeves, pins carried by said sleeves, each pin 100 having a loop intermediate its ends, a bolt pivotally mounted upon one loop and extending through the remaining loop, a nut carried upon the bolt, whereby when the nut is tightened upon the bolt the ends of the 105 band will be drawn toward each other for holding the band in firm engagement with the ends of the sections.

2. In a device of the class described, the combination of a thimble consisting of a 110 neck adapted to be connected to a stove pipe section, an annular collar formed upon said neck, a corrugated portion extending beyond the opposite side of said collar, a turn buckle, threaded stems carried by said turn 115 buckle, semi-circular heads carried upon the outer ends of said stems and engaging the inner surface of the corrugated portions of said thimble, whereby when said turn buckle is adjusted it will move the heads apart for 120 causing the heads to slightly expand the corrugated portion of the thimble for firmly binding the same in engagement with a chimney.

3. In a device of the class described, the 125 combination of a plurality of stove pipe sections, a clamping band positioned upon the ends of said sections, plates fixed upon said band adjacent its ends, said plates have sleeves, pins carried by said sleeves, each 130

pin having a looped portion intermediate its ends, a bolt pivotally mounted upon one looped portion and extending through the remaining looped portion, a nut carried by the bolt whereby when the nut is tightened upon the bolt the ends of the band will be drawn toward each other for holding the band in firm engagement with the ends of the sections.

4. In a device of the class described, the combination of a thimble including a corrugated portion, said thimble being adapted to be connected to a stove pipe section, a turn buckle, threaded stems carried by said turn buckle, semi-circular heads carried upon the outer ends of said stems and engaging the inner surface of the corrugated portions, of said thimble, whereby when said turn buckle is adjusted it will move the heads apart for causing the heads to slightly expand the

corrugated portions of the thimble for firmly binding the same in engagement with the chimney.

5. In a device of the class described, the combination of a thimble including a corrugated portion, said thimble being adapted to be connected to a stove pipe section, an expansible means positioned within the thimble and including heads engaging the corrugated portion of said thimble, whereby when said means is expanded it will expand the corrugated portion of the thimble for firmly binding the same in engagement with a chimney.

In testimony whereof I affix my signature in presence of two witnesses.

ELMER A. PETERSON.
